CLAIM

The ornamental design for an electronic computer, as shown and described.

DESCRIPTION

FIG. 1 is a top, front and right side perspective view of an electronic computer showing our new design,
FIG. 2 is a front elevational view thereof,
FIG. 3 is a right side elevational view thereof,
FIG. 4 is a left side elevational view thereof,
FIG. 5 is a rear elevational view thereof,
FIG. 6 is a top plan view thereof,
FIG. 7 is a bottom plan view thereof,
FIG. 8 is a top plan view showing the article in a closed position thereof,
FIG. 9 is a front elevational view showing the article in the closed position thereof; and,
FIG. 10 is a right side elevational view showing the article in the closed position thereof.
